FORMING MACHINE

Frederik J. Borup, Stratford, Conn.

Application December 17, 1947, Serial No. 792,142

12 Claims. (Cl. 90—13.6)

1

This invention relates to new and useful improvements in forming machines and has particular relation to a machine for making metal patterns for use in precision casting.

An object of the invention is to provide a machine whereby metal patterns of great precision may be manufactured with a great savings of time and labor and thus of expense.

Another object is to provide a forming machine for precisely producing metal patterns such, for example, as metal patterns to be used in the producing of the blades of a jet turbine.

A further object is to provide a machine adapted to produce on a smaller scale and with great accuracy a replica of a large pattern, which large pattern may be hand made of wood or the like, to the end that any errors in the pattern are reduced in the smaller replica and the latter is thereby made of great accuracy and at comparatively low cost.

More specifically, an object of the invention is to provide a forming machine adapted to reproduce on a small scale a relatively large hand made pattern involving many slight generated curves.

Other objects and advantages of the invention will become apparent from a consideration of the following detailed description taken in connection with the accompanying drawings wherein satisfactory embodiments of the invention are shown. However, it is to be understood that the invention is not limited to the details disclosed but includes all such variations and modifications as fall within the spirit of the invention and the scope of the appended claims.

In the drawings:

Fig. 1 is a front elevational view of a forming machine made in accordance with the invention, the machine being adapted for support on a work bench or the like;

Fig. 2 is a plan view of said machine;

Fig. 3 is a horizontal sectional view taken as along the line 3—3 of Fig. 1;

Fig. 4 is an enlarged front elevational view of a carriage and its supporting or mounting structure and associated parts;

Fig. 5 is an edge elevational view taken as looking from the right in Fig. 4;

Fig. 6 is a sectional view taken as along the line 6—6 of Fig. 1;

Fig. 7 is a sectional view taken as along the line 7—7 of Fig. 4;

Fig. 8 is a sectional view taken as along the line 8—8 of Fig. 4;

Fig. 9 is a side elevational view of the carriage

and its supporting and associated parts but with certain modifications;

Fig. 10 is an elevational view looking from the left in Fig. 9;

Fig. 11 is a view similar to Fig. 1 but showing a modification; and

Fig. 12 is an enlarged sectional view taken as along the line 12—12 of Fig. 11.

Referring in detail to the drawings and at first more particularly to Figs. 1—8, my improved forming machine is shown as including a hollow base 10 which may be a casting or several castings, as convenience indicates, and which is provided with end flanges 11 and side flanges 12, all provided with perforations 13. Clearly, the base 10 is adapted to be disposed on a bench or table or similar support and may be fastened in place by passing screws or bolts through the perforations 13. All of the mechanism of the present forming machine is mounted on the base 10 and thus it will be seen that the entire machine may be shifted as a unit from any one bench or place to another and it will also be clear that the machine may be conveniently mounted on any bench or table-like support whether the latter is portable or not.

The mechanism mounted on the base 10 includes a work support generally designated 14, a pattern support generally designated 15, a mounting structure generally designated 16, a carriage generally designated 17 and slideable or reciprocable in said mounting 16, a tracer mounting means generally designated 18 and shown in the form of a pantograph and mounted on said structure 16, and a tool or cutter mounting means generally designated 19 and also disclosed as a pantograph means mounted on said structure 16. A work piece is designated 20 and the same as here disclosed comprises a cast metal piece and in the drawings is shown by broken lines. This piece may be cast to the general shape of the finished product but contains ample material for removal whereby the finished product will be of the exact dimensions and contours desired.

Work piece 20 is provided at its upper and lower ends with studs or extensions 21 and such lower extension is shown as gripped in a chuck device 22 while the upper end or extension is received in a vertically adjustable tubular bearing element 23. Chuck 22 is shown as having its shank 24 gripped in a head or collar 25 as by means of a set screw 26 and said head or collar 25 is integral with or is otherwise made turnable with a vertical shaft 27 having a bearing 28 in a casting

29 and also having a bearing 30 in the upper wall portion 31 of one end portion of the base casting 10.

The shaft 27 enters such hollow base casting and therein has affixed to it a bevelled gear 32, the purpose of which will appear. The hollow step-like casting 29 is shown as secured to one end portion of the base casting 10 and as actually bolted to the wall 31 of such portion. The bolts for this purpose are designated 33. On the upper side of the step-like casting 29, a cast or otherwise formed bracket arm 34 has its lower portion secured to the casting 29 as by bolts 35. At its upper end, the casting 34 includes an inwardly directed arm 36 provided with an enlarged or hub-like bearing portion or ring 37 in which the element 23 is turnable and through which said element is vertically adjustable. It will be understood that the element 23 is adjusted vertically up and down whereby longer work pieces 20 may be accommodated between such element and the chuck means 22.

The studs 21 on the end of a work piece being received in the chuck and in the inner end of the element 23, the latter is fixed in this vertically adjusted position by tightening of a set screw 38. While the drive means will later be set forth, here it is noted that on the gear 32 being driven, shaft 27 is driven and through the chuck means 22 causes rotation of the work piece 20. At this time, the stud 21 at the upper end of the workpiece turns in the element 23, the latter being held against turning movement by the set screw 38.

The pattern support 15 is illustrated as mounting or supporting a pattern or control element generally designated 39 and shown by broken lines. This pattern is provided with stud-like extensions 40 at its upper and lower ends and it will be understood that the pattern is made on a predetermined scale with respect to the size of the finished work piece. Thus, the pattern may be made five times the actual size of the desired product and preferably is made of wood and made as closely as possible to the actual contours which are desired in the finished work piece. In the event that a scale of five to one is used, it will be understood that the studs 40 need not be to scale but should be properly located for the proper mounting of the pattern.

The lower stud 40 is shown as secured in a collar or chuck 41 by means of a set screw 42 and such collar is provided with a shank or extension 43 clamped in a collar or enlarged diameter flange portion 44 as by a set screw 45. Shank 43 is thus received and suitably fixed to and in concentric relation with a shaft 46 having bearing in the upper wall portion 47 toward one end of the casting 10. In this connection it is noted that flange portion 44 is integral with the shaft 46 and supports the latter against casual downward movement. Fixed to the shaft 46 within such casting 10 is a bevelled gear 48 corresponding with the bevelled gear 32 previously mentioned.

Also fixed to the upper side of the base wall portion 47, as by bolts 49, is the base portion of a bracket 50 which also may be a casting. At its upper end bracket 50 includes a forwardly extending arm portion 51, the forward end of which carries a bearing 52 located above and concentric with the shaft 46, stud 43, etc. Through the bearing 52 passes a vertically adjustable bearing element 53, the lower end of which receives the upper stud 40 of the pattern 39. With the de-

scribed construction it will be appreciated that when the gear 48 is rotated, the pattern 39 will be rotated. At such times the upper stud 40 of the pattern rotates in the bearing element 53 since the latter is held in vertically adjusted position by being clamped with a set screw 54. Thus, when the pattern is driven the element 53 is stationary.

It will be appreciated that the pattern 39 being of definite ratio to the work piece 20, when a longer or shorter work piece is mounted by the work support 14 entailing adjustment of the bearing element 23, then a longer or shorter pattern 39 will be mounted in the pattern support 15 entailing adjustment of the bearing element 53. Further, as the description proceeds, it will become more apparent that the pattern must be mounted with its mid portion in a definite relationship to the mid portion of the work piece. That is, if the work piece is three inches long, for example, the pattern may be fifteen inches long. Under such circumstances, the mid point of the pattern, that is seven and one-half inches from either end, must be in horizontal alignment with the mid portion of the work piece, that is one and one-half inches from either end of the work piece. Under these circumstances, adjustment of the bearing element 53 only for the mounting of the pattern will not suffice.

Thus, other chuck or collars 41 may be used if the new pattern is shorter or thicker or thinner shims may be inserted between the collar or chuck 41 and the flange 44, all as circumstances require. In this particular connection it is noted that the shank 43 of chuck 41 is of considerable length so as to provide for the mounting of shims about said shank.

Suitably mounted as in horizontally spaced bearings 55 in the base 10 is a horizontally disposed longitudinally extending shaft 56. This shaft carries bevelled gears 57 and 58 meshing, respectively, with the bevelled gears 32 and 48 heretofore mentioned. With this construction, it will be clear that on rotation of the shaft 56, the work piece 20 and the pattern 39 will be rotated about their vertical longitudinal axes. The work piece and the pattern, according to the invention, are rotated in synchronism and thus it will be understood that the gears 32 and 48 are identical and that the gears 57 and 58 are identical. Under such circumstances the work piece and pattern will be rotated in synchronism.

Fixed to one end of the shaft 56 is a hand wheel 59 which may be used for shifting the parts when setting up the machine or the like. When the machine is in operation, it is to be driven by an electric motor 60 through suitable reduction gearing 61, the output shaft 62 of which carries a bevelled wheel 63 in mesh with a bevelled wheel 64 fixed to a mid portion of the shaft 56.

With this construction, it will be understood that any time the motor 60 is energized the work piece and pattern will be caused to rotate about their vertical longitudinal axes. If desired, any clutch or other known means may be used whereby the drive between the motor 60 and the shaft 56 may be interrupted so that the shaft will be more freely turnable by the hand wheel 59 when such an action is desirable.

It is clear that the work support 14 and the pattern support 15 are located toward opposite ends of the base casting 10 and (see Figs. 2 and 3) the axes of the work piece and pattern are in the same vertical plane. The step-like casting 29 at its inner portion or its portion toward the

mid point of the casting 10 is provided with a relatively heavy bearing 65 depending from its upper wall 66. This bearing receives and mounts a vertically disposed relatively heavy or large diameter stud or shaft 67 provided at the upper side of the wall 66 with a flange-like collar 68 and extending through and above said collar in a reduced diameter portion 69.

The stud portion 69 enters into a bottom block-like portion 70 (see Figs. 4 and 5) of the mounting structure 16. In addition to said block-like portion 70, the mentioned structure includes front and rear vertically disposed plates 71 and 72 clamped to and against the block 70 as by bolts 73 and at their upper ends spaced by and clamped against a block 74 as by means of screws or bolts 75.

It will be noted that the portions 70, 71, 72 and 74 constituting the mounting structure 16 are each of a heavy rigid construction whereby the entire mounting structure is rigid and the same is in the form of a hollow oblong open at its sides. Secured by bolts 76 to the inner surface of the front plate 71 (see Fig. 7) of the mounting structure are a pair of spaced parallel guide bars or rails 77 and fastened by bolts 78 to the inner surface of the rear plate 72 of the mounting structure are a pair of spaced parallel guide bars or rails 79. The rails 77 are arranged exactly opposite the rails 79 and in opposing relation therewith.

The carriage 17 is a block-like structure somewhat in the shape of a Greek cross including a body structure 80 having portions 81 and 82 of reduced thickness and slidably fitting between the pair of guide rails 77 and the pair of guide rails 79, respectively. In addition, pairs of ears 83 and 84 project from the lower portions of the opposite edges of the body 80 for a purpose to be described. These ears project toward the open sides or edges of the above described hollow oblong mounting structure 16.

The lower block 70 of such structure rests on the collar 68 and is secured to the stud-like extension 69 by dowels 73a. Said extension is integral with larger diameter stud shaft 67 mounted in the bearing 65. From this, it will be seen that the entire structure 16 may turn or oscillate about its longitudinal axes, the center of any such turning or oscillation being the center of the stud shaft 67.

To the rear of the mounting structure 16 a bracket 85 is secured to the casting wall 66 as by screws or bolts 86 and such bracket includes an upper forwardly extending arm portion 87 having a bearing ring 88 at its forward end. Passing through and turnable in said ring is a shaft 89 to the upper end of which is fastened a hand wheel 90 and the lower portion of which is threaded as at 91. This shaft 89 may be integral with an enlarged diameter portion 92 resting on the upper side of the block 74 and filling the space between such block and the lower side of the bearing ring 88.

A filler means 93 may be integral with the upper side of said bearing means and fills the space between the latter and the hand wheel and, in fact, may constitute a hub-like portion of said hand wheel. The shaft 89 passes through the upper end block 74 of the hollow oblong constituting the mounting structure 16 and within said structure is threaded into and through the carriage 17. Clearly, with this arrangement, the screw threads 91 prevent gravitational downward movement of the carriage 17 but on turning of the hand wheel 90 said carriage may be fed or

slid upwardly or downwardly, depending on the direction in which the hand wheel is turned.

On turning of the hand wheel, the carriage will slide since the shaft 89 will turn with the hand wheel and is threaded to the carriage and such shaft is held against longitudinal movement while the carriage is held by the guide rails 77 and 79 against turning movement but is clearly adapted for guiding reciprocations between said guide rails.

Below the guide rails 77 and 79 and extending between and mounted by the front and rear walls 71 and 72 of the described hollow oblong structure 16 are upper and lower pins or shafts 94 and 95. The pins or shafts 94 and 95 are parallel with one another and are in vertical alignment and are so located that their axial center lines are at right angles to the axial center line of the shaft or lead screw 89. These pins or short shafts pivotally mount the inner ends of a pair of arms 96 and 97 constituting portions of a pantograph structure embodied in the tracer mounting 18 and they also form pivotal mountings for the inner ends of a pair of parallel arms 98 and 99 constituting portions of a pantograph structure forming a part of the cutter or tool mounting means generally designated 19.

To the desired end (see especially Fig. 8) the inner end portions of the arms 96 and 97 are enlarged providing head-like portions 100 located between the front and rear plates 71 and 72 of the mounting structure 16 and of a width substantially equal to the distance between the inner surfaces of said plates. Each head-like portion is mounted on one of the pivot means 94 and 95 and is bifurcated as at 101. The links or arms 98 and 99 have their inner end portions received in the bifurcations 101 of the respective arms 96 and 97 and are pivotally mounted on the respective means 94 and 95. In this way, the arms 96 and 98 are mounted on one pivot means 94 while the arms 97 and 99 are mounted on the other pivot means 95.

A link 102 is pivoted at its upper end and as at 103 to the ears 84 on the carriage 17 and at its lower end is pivoted as at 104 to the above described arm 96. Somewhat similarly, a link 105 is pivoted at its upper end at 106 to the ears 83 on the carriage and this link at its lower end is pivoted as at 107 to the arm 98 of the tool or cutter mounting means 19.

At their outer ends, the arms 96 and 97 are pivoted as at 108 and 109 to a web-like portion 110 of a piece or casting generally designated 111. The web 110 constitutes a rigid connection between the pivots 108 and 109 and thus between the outer ends of the arms 96 and 97 being rigid are always in exactly parallel relation.

From the web 110 the device or means 111 includes a forwardly directed arm 112 having a bifurcated head-like portion 113 at its free end and in which is mounted a tracer 114. This tracer is shown as mounted on a pin 115 extending between the portions of the bifurcated head 113 whereby the tracer is mounted in such manner that it is free to turn on the axis constituted by the pin 115. It is noted with reference to Fig. 1 that while the arms 96 and 97 are inclined, the forwardly projecting arm 112 of the member or casting 111 is horizontal. It is also noted that the arms 96 and 97 comprise portions of a pantograph including the rigid web-like portion 110 of the member 111.

The arms 98 and 99 at their outer ends are pivotally connected as at 116 and 117 to spaced portions of a rigid bracket structure 118. The dis-

7
tance between the pivots 116 and 117 is the same as that between the pivots 94 and 95 and thus the arms 98 and 99 constitute portions of a pantograph structure and are always in parallel relation. Similarly, the bracket structure 118 being rigid, it will always remain in upright condition as the arms 98 and 99 are rocked about or with the pivots 94 and 95.

Bracket-like structure 118 includes a bifurcated head portion 119 between the arms of which is located any suitable tool or cutter 120, the same being mounted as on a shaft 121. Through a coupling 122, this shaft is designed to be driven by a flexible drive shaft 123 extending from a motor 124 secured to the bracket 118 as by a mounting or clamping means 125. A suitable covering 126 is preferably located about or over the flexible drive shaft 123. With this structure, it will be seen that when the electric motor 124 is operating it will through the shaft 123 and the coupling 122 serve to rotate the tool or cutter 120 on the axis constituted by the means 121.

Fastened to or preferably integral with the casting 50 is a laterally extending arm 127 at its outer end mounting a shaft 128 on which is located a pulley or idler 129. A flexible element 130 is trained over such pulley or idler and has one end connected to the rigid member 111 as by a bail 131 and secured to the other end of said flexible member is a counter-weight 132. By comparison of Figs. 1, 2 and 6, it will be noted that the idler or pulley 129 is not only located substantially above the tracer carrying member 111 but is also located substantially rearwardly of such member. It will later become more apparent, but here it is noted that the counter weight 132, because of the relative location of the parts, acts as a counter-balance to pull upwardly on the tracer carrying means 18 and also exerts a rearward pull on such means in such manner as to tend to rock the mounting structure 16 on the axis constituted by the shaft 67 in a direction to carry the tracer 114 rearwardly. The effect of this action is to insure that the tracer 114 is constantly kept in contact with the pattern 39.

While the machine of the invention may be used for other purposes and while certain features of the machine may be used without other features and the like, the machine as described is particularly designed for the making of metal patterns to be used in casting the blades of turbine motors. The contours of the blades of jet turbines are very carefully calculated and at the present time in making metal patterns for such blades many hours and days are consumed in the making of a single pattern. This is because the contours are constantly changing and the work is substantially entirely all hand work by highly skilled mechanics. With the present machine metal patterns of great accuracy may be produced with a great savings in time and cost over the hand method.

According to the present invention, a pattern 39 is made up of wood or other desired material. This pattern may be made on the desired scale but it is suggested that if the pattern is made five times actual size a substantial piece of work results. The pattern is made as closely as possible to the desired size, shape and contour all in the desired ratio. Then the pattern is mounted in the pattern support 15. At the same time or thereafter a suitable work piece 20 is mounted in the work support 14 and the work piece will be in the form of a casting. The location of the

8
idler 129 resulting in a rearward pull as well as an upward pull on the member 111, the tracer 114 is kept against the pattern since the pull of the counter weight tends to move the tracer rearwardly, the view in Fig. 1 being considered the front of the machine.

The carriage mounting structure 16 being turnable with the stud 67 as an axis may be located in the desired position to permit the tracer to engage the pattern 39. At the same time, while the tracer engages the front or forward side or portion of the pattern, the tool or cutter 120 will be engaging the rear side of the work piece 20 (see Fig. 2). Thus, the tendency of the counter weight to maintain the tracer against the pattern also results in the cutter being maintained against the rear side of the work piece. This is true since both the tracer mounting means 18 and the cutter mounting means 19 are anchored to or attached to the mounting structure 16 for the slide 17. In the initial set-up the pattern and work piece are therefore disposed at one hundred and eighty degrees (180°) to one another owing to the engagement of the opposite portions of these items by the tracer and tool, respectively.

The pattern and work piece being positioned as described, the motor 60 may be set into operation. It will be understood that when mounting the pattern and work piece, the pattern is so located that a point midway its length is horizontally in alignment with the point midway the length of the work piece. As the motor 60 operates through the reduction gearing 61 and the other gearing described, shaft 56 is turned and applies rotary movement to the pattern and work through the shaft 46 and mount 41, etc. and the work piece through the shaft 21, chuck 22, etc. As the pattern and work slowly rotate about their parallel vertical axes, the tracer 114 rides against the surface of the pattern and the cutter 120 is kept against the face of the work. In this connection it is to be understood that if the pattern is on a scale of five to one relative to the work piece, then all other parts are in proportion. Thus, the tracer 114 would be five times the diameter of the cutter 120 and the pantograph structures mounting the tracer and cutter would be in the ratio of five to one. It is, of course, to be understood that this ratio of five to one is merely suggested by way of example since any other desired ratio may be employed.

As the work piece and pattern rotate and are engaged by the tracer and tool, respectively, the hand wheel 90 is operated. This hand wheel is manually operated to raise the carriage 17 and such action through the links 102 and 105 will swing the pantograph structures on the pivots 94 and 95 and raise the tracer and tool along the pattern and work. As the tracer and tool reach the top of the pattern and work the operator reverses the direction in which he turns the hand wheel 90 to thereby slide the carriage 17 downwardly between the pairs of guide rails 77 and 79, respectively, to move the tracer and tool downwardly over the pattern and work. Because of the pantograph structures employed the axes of the traces and tool will remain vertical and parallel as the tracer and tool mounting or supporting structures 18 and 19 are raised and lowered by being swung on the pivots 94 and 95. That is, in any position of the means 18 and 19, from their lowermost to their uppermost extremes, the tracer and the tool bear the same relation to the work and they are not inclined

as the means 18 and 19 incline at one side or the other of horizontal center.

As the pattern and work are being turned during this movement of the tracer and tool, the latter instrumentalities will engage the pattern and work over spiral lines. Since the structure 16 may pivot about the axis of the stud 67, it will be seen that both the stylus mounting means and the tool mounting means may swing horizontally as wider or narrower portions of the pattern press against the tracer. However, corresponding portions of the work piece will face the cutter 120 and so the latter remains in contact with the work piece at all times. The position and the connections of the counter weight with the stylus mounting means 18 insures that the stylus will remain against the pattern and the tool will remain against the work. It will be understood that during these operations the electric motor 124 is energized and through the flexible shaft 123 and coupling 122 is driving the tool or cutter 120.

The form which the tool or cutter 120 takes is not here controlling since the tool or cutter may be in the nature of a small milling cutter or of a small grinding wheel such as a diamond grinding wheel, or the like. In any event, through the hand wheel 90, the carriage 17 is reciprocated up and down in a path parallel with the axes of the pattern support and the work support and at each reciprocation the tool is passed over the slowly revolving work piece. With the described construction it will be apparent that due to the ratio of the various parts, any slight errors in the pattern 39 will be reproduced only to a small degree in the work piece. Thus, if the ratios employed are five to one and the pattern is carefully made, any small error in the pattern will be reduced by four-fifths when it appears in the work piece. Thus, an error of .001 in the pattern will represent an error of but .0002 in the work piece.

From the above, it will be understood that with the present machine skill is required on the part of the mechanic making the pattern 39 but once the machine is set up with that pattern, the operation is nearly mechanical. The only thing required on the part of the operator is that he turn the hand wheel 90 in one direction to feed the tracer and cutter downwardly over the pattern and work and then reverse the direction of turning of the hand wheel to feed the tracer and cutter upwardly over the pattern and work. It is planned that during each stroke the cutter will remove but a slight amount of material. After many strokes of the cutter, each removing a slight amount of material from the work piece but all material being removed to establish the proper contours, a finished and highly accurate pattern is rather quickly (as compared to former methods) and inexpensively made.

Referring now to the modification of Figs. 9 and 10. In this structure the modification consists essentially in that the shaft or feed screw 89 is power driven by a reversible motor. With the exception of the motor and the controls for the same, the parts heretofore described are again employed and for the sake of clarity and brevity have been identified by the reference characters heretofore applied to them.

Thus, in the modification I have the mounting structure 16 and the slide 17 slidable or reciprocable therein as well as the bracket 85. In the modification, the hand wheel 90 heretofore used is omitted and in its place a reversible electric

motor 133 is mounted by the bearing ring or means 88 of the bracket 85. This motor is connected to drive the shaft or lead screw 89 having the lower threaded portion 91 threaded into the carriage 17. Carriage 17 is provided with a finger-like extension 134 located above the ears 83 and which finger-like portion is rigid with the carriage and mounts a vertical rod or bar 135 threaded throughout substantially its entire length.

Mounted on such threaded rod or bar is an upper nut 136 and a lower nut 137 adapted for threaded adjustment along the rod or bar toward and from one another. Fixed to the rear plate 15 of the hollow oblong mounting structure 16 is an L-shaped plate 138 including a portion 139 fastened to plate 12 as by bolts 140 and a relatively long vertical arm 141 extending parallel with the shaft 89. Mounted on the mid portion 15 of the arm 141 is a reversing switch 142 the operating piece or handle 143 of which projects to be engaged by the nuts 136 and 137.

On the upper portion of the arm 141 is mounted a micro-switch 144 held in place as by screws 145 and adapted for vertical adjustment within the limits of a slot 146. Similarly, a micro-switch 147 is mounted on the lower portion of arm 141, in line with the switch 146, and is held in place as by bolts 148 passing through a vertical slot 149 corresponding with the slot 146.

Push buttons or the like 150 of the micro-switch 144, and 151 of the micro-switch 147, project forwardly into positions to be engaged by the nuts 136 and 137. In the construction illustrated in Figs. 9 and 10, the micro-switches 144 and 147 have no part but such switches are shown in these figures since the figures include the means for mounting them and these switches are actually used in connection with the modification shown in Fig. 11.

With the described construction of the modification of Figs. 9 and 10, after the pattern and work have been mounted in their supports the carriage 17 is reciprocated or slid up and down along the paths defined by the guide rails 77 and 79 by the electric motor 133. To this end, the nuts 136 and 137 are adjusted to the proper positions on the threaded rod 135. It will be clear that this rod moves with the slide 17. As the slide moves downwardly, the nut 136 is brought into position to trip the lever 143 whereby to have the motor 133 reverse. This will take place at the lower end of the stroke of the tracer 114 and cutter 120.

When the nut 136 trips the switch 142 and motor 133 reverses, the screw 89 is turned in the opposite direction and feeds the carriage 17 upwardly causing the tracer 114 and the cutter tool 120 to move upwardly over the pattern and work, respectively. At the upper end of the stroke, the nut 137 again trips the switch control 143 whereby the direction of rotation of the motor 133 is again reversed and the drive of the shaft 89 is reversed to again feed the slide downwardly. Thus, it will be understood that the nuts 136 and 137 being properly adjusted, they alternately engage the switch lever 143 reversing the motor 133 at each of the upper and lower limits of movement of the stylus and cutter over the pattern and work.

At the limit of downward movement of the carriage, the nut 137 engages the button 151 of the micro-switch 147 (see Fig. 10) and at the limit of the upward movement of the carriage, the nut 136 engages the button 150 of the upper micro-switch 144. Since these micro-switches are ver-

tically adjustable owing to the provision of the slots 146 and 149, it will be understood that the positions of the micro-switches must be and are changed in accordance with any adjustments of the nuts 136 and 137 on the threaded bar or rod 135. The full purpose of the switches 140 and 147 will be set forth when considering Figs. 11 and 12.

From the above, it will be understood that the structure proposed in Figs. 9 and 10 is substantially the same as that of Figs. 1-8 with the exception that the carriage 17 is to be power driven in each direction by the reversible electric motor 133. This eliminates the occasion for the hand wheel 20 and the labor and attention involved in the manual manipulation of said wheel.

Referring now to the modification of Figs. 11 and 12, the machine there shown is in a large measure the machine previously described and where the parts are the same they are identified by the same reference characters. In the structure of this modification, the reversible electric motor 133 and its control are again employed and further in this modification the micro-switches 144 and 147 exercise their functions.

The new parts involved in the modification comprise a ratchet wheel 152 fast to an intermediate portion of the shaft 56 and associated with said ratchet wheel and movable about said shaft is a lever 153 carrying a pawl 154, normally held in engagement with the ratchet wheel as by a small coil spring 155. Fixed to the lever 153 is the outer end of a plunger 156 of a solenoid magnet 157 located within and fastened to the casting 10 as by the screws 158. The solenoid core and the lever 153 on being moved from their normal position (shown in Fig. 12) and thereafter released, are returned to said normal position as by a coil spring 159 anchored at one end to the lever and at its other end to a wall of the casting 10. Also carried by the casting and suitably located is a stop or limiting device 160 determining the extent of the return movement of the lever 153 under the influence of the spring 159.

The structure of the modification of Figs. 11 and 12 operates much in the manner of the structure first described. However, in the structure first described the work piece 20 and the pattern 39 are constantly rotated in the same direction. Where the pattern and work piece trail off to a rather thin edge difficulty may be encountered with the first described structure as such thin edges work against the tracer and the cutting tool. That is, these thin trailing edges may flex under the described conditions whereby the resultant product would not be true or accurate.

With the device of the modification of Figs. 11 and 12, the pattern and the work piece are rotated in an intermittent manner or in a step-by-step manner. This step-by-step rotation takes place at the end of each stroke of the tracer and cutter whether such stroke be up or down. Therefore, instead of the tracer and tool engaging the pattern and work over a spiral path, they engage the pattern and work over straight vertical paths and there is less, if any, tendency to cause any flexing of thinner or narrower edge portions of the pattern and/or work.

When the machine of Figs. 11 and 12 is placed in operation, the motor 133 and the switch 142 function as heretofore described. However, at the end of a stroke of the carriage (and thus of the tracer and tool) for example, a downward stroke, the nut 137 will engage the button 151 of the micro-switch 147 and close a circuit to

the solenoid magnet 157. As this magnet is energized, it draws inwardly on the core 156 operating the lever 153 about the shaft 56 as a center. This will be a clockwise movement of the lever as viewed in Fig. 12.

As the lever moves it will, operating through its pawl 154, turn the ratchet 152 one step. This will turn the shaft 56 a predetermined amount and through the above described gearing connections, such turning movement of the shaft will be imparted to the pattern and work and the latter will each be rotated or oscillated through a predetermined step or arc. At this time, the nut 136 has engaged and operated the handle 143 of the reversing switch 142 and the motor 133 then operates to feed or slide the carriage 17 upwardly. This carries the nut 137 from the button 151 of micro-switch 147 and the switch opens and the solenoid 157 is de-energized.

Now the spring 159 operates to return the ratchet and solenoid structure to normal position ready for the next operation. At the upper end of the movement of the carriage (and thus of the tracer and tool) the nut 137 trips the reversing switch 142 to reverse the motor 133. At the same time, the nut 136 engages the button 150 of the micro switch 144 again energizing the solenoid magnet 157 to again operate the pawl and ratchet means and advance the shaft 56 a step and to advance the pattern and work a step in the same direction.

Thus, with the structure of the modification, it will be clear that movement of the pattern and work is not continuous as with the structure first described but is intermittent or step-by-step. That is, the pattern and the work are advanced synchronously a step at the end of each stroke of the slide and the tracer and tool controlled by the slide. In this way, a series of fine, very close together, straight parallel cuts are made on the work and there will be no flexing of the pattern and work to result in inaccuracies such as might result when a thin or trailing edge portion of the pattern was forced to act against and shift the tracer and thus the structure 16 and all parts mounted thereby or associated therewith in the machine wherein the pattern and work are continuously rotated about their vertical axes.

From the foregoing it is believed that the scope and spirit of the invention will be apparent. However, it is desired to point out that the tracer and tool may be mounted on opposite ends of a single rigid beam pivoted off-center in the desired ratio. Further, to obtain the desired necessary relative movement between the tool and work piece and the tracer and pattern, the supports for the work piece and for the pattern may be moved vertically or may be moved longitudinally and, in such instance, the carriage may be omitted or need not be moved. Further, in certain timed relation, it is deemed possible that the patterns and work pieces be rotated in opposite directions instead of in the same direction but nevertheless it is felt that the movement of these pieces would be synchronous.

Having thus set forth the nature of my invention, what I claim is:

1. In a forming machine, a base, a pattern support on said base, a work support on said base and spaced horizontally from said pattern support, said supports mounted for turning movement on vertical axes, a carriage support located between said pattern and work supports, means mounting said carriage support on said base for turning movement on a vertical axis

13

substantially horizontally aligned with the axes on which said pattern and work supports are turnable, a carriage slidably mounted on said carriage support, means for sliding said carriage upwardly and downwardly on said carriage support, a pair of arms at their outer ends mounting a tracer and a tool respectively, means anchoring the inner ends of said arms to said carriage support for turning movement therewith about a vertical axis and for swinging movement relative thereto about a horizontal axis, a pair of links pivoted at their inner ends to said carriage and at their outer ends to the respective arms at points spaced from the means anchoring the inner ends of the arms to said carriage support whereby on sliding movement of said carriage on the carriage support the arms are swung about the mentioned horizontal axis, said links connected with the respective arms at points equidistant from the mentioned horizontal axis about which said arms are swingable whereby equal angular movement is imparted to the arms on sliding movement of the carriage on the carriage support, and means constantly tending to turn said carriage support on its vertical axis whereby to maintain a tracer on one of said arms and a tool on the other thereof against the opposite sides of a pattern and a piece of work on said pattern and work supports respectively.

2. In a forming machine, a base, a pattern support on said base, a work support on said base and spaced horizontally from said pattern support, said supports mounted for turning movement on vertical axes, a carriage support located between said pattern and work supports, means mounting said carriage support on said base for turning movement on a vertical axis substantially horizontally aligned with the axes on which said pattern and work supports are turnable, a carriage slidably mounted on said carriage support, means for sliding said carriage upwardly and downwardly on said carriage support, a pair of arms at their outer ends mounting a tracer and a tool respectively, means anchoring the inner ends of said arms to said carriage support for turning movement therewith about a vertical axis and for swinging movement relative thereto about a horizontal axis, a pair of links pivoted at their inner ends to said carriage and at their outer ends to the respective arms at points spaced from the means anchoring the inner ends of the arms to said carriage support whereby on sliding movement of said carriage on the carriage support the arms are swung about the mentioned horizontal axis, said links connected with the respective arms at points equidistant from the mentioned horizontal axis about which said arms are swingable whereby equal angular movement is imparted to the arms on sliding movement of the carriage on the carriage support, means constantly tending to turn said carriage support on its vertical axis whereby to maintain a tracer on one of said arms and a tool on the other thereof against the opposite sides of a pattern and a piece of work on said pattern and work supports respectively, and means for rotating said pattern support and work support in unison as said carriage is slid upwardly and downwardly on the carriage support and said arms are swung on said horizontal axis.

3. In a forming machine, a base, a pattern support on said base, a work support on said base and spaced horizontally from said pattern support, said supports mounted for turning movement on vertical axes, a carriage support located

14

between said pattern and work supports, means mounting said carriage support on said base for turning movement on a vertical axis substantially horizontally aligned with the axes on which said pattern and work supports are turnable, a carriage slidably mounted on said carriage support, means for slidingly reciprocating said carriage upwardly and downwardly on said carriage support, a pair of arms at their outer ends mounting a tracer and a tool respectively, means anchoring the inner ends of said arms to said carriage support for turning movement therewith about a vertical axis and for swinging movement relative thereto about a horizontal axis, a pair of links pivoted at their inner ends to said carriage and at their outer ends to the respective arms at points spaced from the means anchoring the inner ends of the arms to said carriage support whereby on sliding movement of said carriage on the carriage support the arms are swung about the mentioned horizontal axis, said links connected with the respective arms at points equidistant from the mentioned horizontal axis about which said arms are swingable whereby equal angular movement is imparted to the arms on sliding movement of the carriage on the carriage support, means constantly tending to turn said carriage support on its vertical axis whereby to maintain a tracer on one of said arms and a tool on the other thereof against the opposite sides of a pattern and a piece of work on said pattern and work supports respectively, and means for simultaneously imparting step-by-step movements to said pattern support and work support in timed relation with reciprocations of said carriage on said carriage support and upward and downward swinging of said arms on said horizontal axis.

4. In a forming machine, a base, a pattern support on said base, a work support on said base and spaced horizontally from said pattern support, said supports mounted for turning movement on vertical axes, a carriage support located between said pattern and work supports, means mounting said carriage support on said base for turning movement on a vertical axis substantially horizontally aligned with the axes on which said pattern and work supports are turnable, a carriage slidably mounted on said carriage support, means for slidingly reciprocating said carriage upwardly and downwardly on said carriage support, a pair of arms at their outer ends mounting a tracer and a tool respectively, means anchoring the inner ends of said arms to said carriage support for turning movement therewith about a vertical axis and for swinging movement relative thereto about a horizontal axis, a pair of links pivoted at their inner ends to said carriage and at their outer ends to the respective arms at points spaced from the means anchoring the inner ends of the arms to said carriage support whereby on sliding movement of said carriage on the carriage support the arms are swung about the mentioned horizontal axis, said links connected with the respective arms at points equidistant from the mentioned horizontal axis about which said arms are swingable whereby equal angular movement is imparted to the arms on sliding movement of the carriage on the carriage support, means constantly tending to turn said carriage support on its vertical axis whereby to maintain a tracer on one of said arms and a tool on the other thereof against the opposite sides of a pattern and a piece of work on said pattern and work supports respectively, a

feed screw mounted for turning movement about its own longitudinal axis on said carriage support, said feed screw in threaded engagement with said carriage, whereby on turning of the feed screw said carriage is slidably moved in the direction of the length of said feed screw and relative to said carriage support, and an electric motor on said carriage support and connected to drive said feed screw.

5. In a forming machine, a base, a pattern support on said base, a work support on said base and spaced horizontally from said pattern support, said supports mounted for turning movement on vertical axes, a carriage support located between said pattern and work supports, means mounting said carriage support on said base for turning movement on a vertical axis substantially horizontally aligned with the axes on which said pattern and work supports are turnable, a carriage slidably mounted on said carriage support, means for slidably reciprocating said carriage upwardly and downwardly on said carriage support, a pair of arms at their outer ends mounting a tracer and a tool respectively, means anchoring the inner ends of said arms to said carriage support for turning movement therewith about a vertical axis and for swinging movement relative thereto about a horizontal axis, a pair of links pivoted at their inner ends to said carriage and at their outer ends to the respective arms at points spaced from the means anchoring the inner ends of the arms to said carriage support whereby on sliding movement of said carriage on the carriage support the arms are swung about the mentioned horizontal axis, said links connected with the respective arms at points equidistant from the mentioned horizontal axis about which said arms are swingable whereby equal angular movement is imparted to the arms on sliding movement of the carriage on the carriage support, means constantly tending to turn said carriage support on its vertical axis whereby to maintain a tracer on one of said arms and a tool on the other thereof against the opposite sides of a pattern and a piece of work on said pattern and work supports respectively, a feed screw mounted for turning movement about its own longitudinal axis on said carriage support, said feed screw in threaded engagement with said carriage whereby on turning of the feed screw said carriage is slidably moved in the direction of the length of said feed screw and relative to said carriage support, an electric motor on said carriage support and connected to drive said feed screw, said electric motor a reversible motor, reversing switches on said carriage support, and means movable with said carriage and engageable with said switches at predetermined times to reverse said motor and thereby the direction of rotation of said feed screw and the direction of sliding movement of said carriage.

6. In a forming machine, a base, a pattern support on said base, a work support on said base and spaced horizontally from said pattern support, said supports mounted for turning movement on vertical axes, a carriage support located between said pattern and work supports, means mounting said carriage support on said base for turning movement on a vertical axis substantially horizontally aligned with the axes on which said pattern and work supports are turnable, a carriage slidably mounted on said carriage support, means for sliding said carriage upwardly and downwardly on said carriage support, a pair of arms at their

outer ends mounting a tracer and a tool respectively, means anchoring the inner ends of said arms to said carriage support for turning movement therewith about a vertical axis and for swinging movement relative thereto about a horizontal axis, rigid means pivotally connecting said carriage to the respective arms at points spaced from the means anchoring the inner ends of the arms to said carriage support whereby on sliding movement of said carriage on the carriage support the arms are swung about the mentioned horizontal axis, said means connected with the respective arms at points equidistant from the horizontal axis about which said arms are swingable whereby equal angular movement is imparted to the arms on sliding movement of the carriage on the carriage support, and means constantly tending to turn said carriage support on its vertical axis whereby to maintain a tracer on one of said arms and a tool on the other thereof against the opposite sides of a pattern and a piece of work on said pattern and work supports respectively.

7. In a forming machine, a base, a pattern support on said base, a work support on said base and spaced horizontally from said pattern support, said supports mounted for turning movement on vertical axes, a carriage support located between said pattern and work supports, means mounting said carriage support on said base for turning movement on a vertical axis substantially horizontally aligned with the axes on which said pattern and work supports are turnable, a carriage slidably mounted on said carriage support, means for sliding said carriage upwardly and downwardly on said carriage support, a pair of arms at their outer ends mounting a tracer and a tool respectively, means anchoring the inner ends of said arms to said carriage support for turning movement therewith about a vertical axis and for swinging movement relative thereto about a horizontal axis, rigid means pivotally connecting said carriage to the respective arms at points spaced from the means anchoring the inner ends of the arms to said carriage support whereby on sliding movement of said carriage on the carriage support the arms are swung about the mentioned horizontal axis, said means connected with the respective arms at points equidistant from the mentioned horizontal axis about which said arms are swingable whereby equal angular movement is imparted to the arms on sliding movement of the carriage on the carriage support, means constantly tending to turn said carriage support on its vertical axis whereby to maintain a tracer on one of said arms and a tool on the other thereof against the opposite sides of a pattern and a piece of work on said pattern and work supports respectively, a pair of links pivoted at their inner ends to said carriage and at their outer ends to the respective arms at points spaced from the means anchoring the inner ends of the arms to said carriage support whereby on sliding movement of said carriage on the carriage support the arms are swung about the mentioned horizontal axis, said links connected with the respective arms at points equidistant from the mentioned horizontal axis about which said arms are swingable whereby equal angular movement is imparted to the arms on sliding movement of the carriage on the carriage support, means constantly tending to turn said carriage support on its vertical axis whereby to maintain a tracer on one of said arms and a tool on the other thereof against the opposite sides of a pattern and a piece of work on said pattern and work supports respectively, and said arms each comprising a pantograph-like structure whereby said tracer and tool are always at the same angle with respect to a pattern on said pattern support and a work piece on said work support in all of the various positions to which said arms may be swung about the mentioned horizontal axis on both upward and downward sliding movements of the carriage on said carriage support.

8. In a forming machine, a base, a pattern support on said base, a work support on said base and spaced horizontally from said pattern support, said supports mounted for turning movement on vertical axes, a carriage support located between said pattern and work supports, means mounting said carriage support on said base for turning movement on a vertical axis substantially horizontally aligned with the axes on which said pattern and work supports are turnable, a carriage slidably mounted on said carriage support, means for sliding said carriage upwardly and downwardly on said carriage support, a pair of arms at their outer ends mounting a tracer and a tool respectively, means anchoring the inner ends of said arms to said carriage support for turning movement therewith about a vertical axis and for swinging movement relative thereto about a horizontal axis, rigid means pivotally connecting said carriage to the respective arms at points spaced from the means anchoring the inner ends of the arms to said carriage support whereby on sliding movement of said carriage on the carriage support the arms are swung about the mentioned horizontal axis, said means connected with the respective arms at points equidistant from the horizontal axis about which said arms are swingable whereby equal angular movement is imparted to the arms on sliding movement of the carriage on the carriage support, and means constantly tending to turn said carriage support on its vertical axis whereby to maintain a tracer on one of said arms and a tool on the other thereof against the opposite sides of a pattern and a piece of work on said pattern and work supports respectively.

tially horizontally aligned with the axes on which said pattern and work supports are turnable, a carriage slidably mounted on said carriage support, means for sliding said carriage upwardly and downwardly on said carriage support, a pair of arms at their outer ends mounting a tracer and a tool respectively, means anchoring the inner ends of said arms to said carriage support for turning movement therewith about a vertical axis and for swinging movement relative thereto about a horizontal axis, a pair of links pivoted at their inner ends to said carriage and at their outer ends to the respective arms at points spaced from the means anchoring the inner ends of the arms to said carriage support whereby on sliding movement of said carriage on the carriage support the arms are swung about the mentioned horizontal axis, said links connected with the respective arms at points equidistant from the mentioned horizontal axis about which said arms are swingable whereby equal angular movement is imparted to the arms on sliding movement of the carriage on the carriage support, means constantly tending to turn said carriage support on its vertical axis whereby to maintain a tracer on one of said arms and a tool on the other thereof against the opposite sides of a pattern and a piece of work on said pattern and work supports respectively, and said arms each comprising a pantograph-like structure whereby said tracer and tool are always at the same angle with respect to a pattern on said pattern support and a work piece on said work support in all of the various positions to which said arms may be swung about the mentioned horizontal axis on both upward and downward sliding movements of the carriage on said carriage support.

9. In a forming machine, a base, a pattern support on said base, a work support on said base and spaced horizontally from said pattern support, said supports mounted for turning movement on vertical axes, a carriage support located between said pattern and work supports, means mounting said carriage support on said base for turning movement on a vertical axis substantially horizontally aligned with the axes on which said pattern and work supports are turnable, a carriage slidably mounted on said carriage support, means for slidably reciprocating said carriage upwardly and downwardly on said carriage support, a pair of arms at their outer ends mounting a tracer and a tool respectively, means anchoring the inner ends of said arms to said carriage support for turning movement therewith about a vertical axis and for swinging movement relative thereto about a horizontal axis, a pair of links pivoted at their inner ends to said carriage and at their outer ends to the respective arms at points spaced from the means anchoring the inner ends of the arms to said carriage support whereby on sliding movement of said carriage on the carriage support the arms are swung about the mentioned horizontal axis, said links connected with the respective arms at points equidistant from the mentioned horizontal axis about which said arms are swingable whereby equal angular movement is imparted to the arms on a sliding movement of the carriage on the carriage support, means constantly tending to turn said carriage support on its vertical axis whereby to maintain a tracer on one of said arms and a tool on the other thereof against the opposite sides of a pattern and a piece of work on said pattern and work supports respectively, a feed screw mounted for turning movement about

its own longitudinal axis on said carriage support, said feed screw in threaded engagement with said carriage whereby on turning of the feed screw said carriage is slidably moved in the direction of the length of said feed screw and relative to said carriage support, an electric motor on said carriage support and connected to drive said feed screw, said electric motor a reversible motor, reversing switches on said carriage support, means movable with said carriage and engageable with said switches at predetermined times to reverse said motor and thereby the direction of rotation of said feed screw and the direction of sliding movement of said carriage, and means for simultaneously imparting a step-by-step turning movement to said work support and to said pattern support on each reversal of said electric motor.

10. In a forming machine, a base, a pattern support on said base, a work support on said base and spaced horizontally from said pattern support, said supports mounted for turning movement on vertical axes, a carriage support located between said pattern and work supports, means mounting said carriage support on said base for turning movement on a vertical axis substantially horizontally aligned with the axes on which said pattern and work supports are turnable, a carriage slidably mounted on said carriage support, means for slidably reciprocating said carriage upwardly and downwardly on said carriage support, a pair of arms at their outer ends mounting a tracer and a tool respectively, means anchoring the inner ends of said arms to said carriage support for turning movement therewith about a vertical axis and for swinging movement relative thereto about a horizontal axis, a pair of links pivoted at their inner ends to said carriage and at their outer ends to the respective arms at points spaced from the means anchoring the inner ends of the arms to said carriage support whereby on sliding movement of said carriage on the carriage support the arms are swung about the mentioned horizontal axis, said links connected with the respective arms at points equidistant from the mentioned horizontal axis about which said arms are swingable whereby equal angular movement is imparted to the arms on sliding movement of the carriage on the carriage support, means constantly tending to turn said carriage support on its vertical axis whereby to maintain a tracer on one of said arms and a tool on the other thereof against the opposite sides of a pattern and a piece of work on said pattern and work supports respectively, said means for slidably reciprocating said carriage upwardly and downwardly comprising a feed screw mounted for turning movement about its own longitudinal axis on said carriage support, said feed screw having threaded engagement with said carriage and extending above the upper end of said feed screw for manually turning the latter in a selected direction whereby to feed said carriage in a selected direction on said carriage support.

11. In a forming machine, a base, a pattern support on said base, a work support on said base and spaced horizontally from said pattern support, said supports mounted for turning movement on vertical axes, a carriage support located between said pattern and work supports, means mounting said carriage support on said base for turning movement on a vertical axis substantially horizontally aligned with the axes on which said pattern and work supports are turnable, a car-

riage slidinely mounted on said carriage support, means for sliding said carriage upwardly and downwardly on said carriage support, a pair of arms at their outer ends mounting a tracer and a tool respectively, means anchoring the inner ends of said arms to said carriage support for turning movement therewith about a vertical axis and for swinging movement relative thereto about a horizontal axis, a pair of links pivoted at their inner ends to said carriage and at their outer ends to the respective arms at points spaced from the means anchoring the inner ends of the arms to said carriage support whereby on sliding movement of said carriage on the carriage support the arms are swung about the mentioned horizontal axis, said links connected with the respective arms at points equidistant from the mentioned horizontal axis about which said arms are swingable whereby equal angular movement is imparted to the arms on sliding movement of the carriage on the carriage support, means constantly tending to turn said carriage support on its vertical axis whereby to maintain a tracer on one of said arms and a tool on the other thereof against the opposite sides of a pattern and a piece of work on said pattern and work supports respectively, an electric motor mounted on the arm the outer end of which mounts said tool, said arm mounting said tool for rotation relative to the arm, and a driving connection between said electric motor and said tool for rotating the latter from the former.

12. In a forming machine, a base, a pattern support on said base, a work support on said base and spaced horizontally from said pattern support, said supports mounted for turning movement on vertical axes, a carriage support located between said pattern and work supports, means mounting said carriage support on said base for turning movement on a vertical axis substantially horizontally aligned with the axes on which said pattern and work supports are turnable, a carriage slidinely mounted on said carriage support, means for slidinely reciprocating said carriage upwardly and downwardly on said carriage support, a pair of arms at their outer ends mounting a tracer and a tool respectively, means anchoring the inner ends of said arms to said carriage support for turning movement therewith about a vertical axis and for swinging movement

relative thereto about a horizontal axis, a pair of links pivoted at their inner ends to said carriage and at their outer ends to the respective arms at points spaced from the means anchoring the inner ends of the arms to said carriage support whereby on sliding movement of said carriage on the carriage support the arms are swung about the mentioned horizontal axis, said links connected with the respective arms at points equidistant from the mentioned horizontal axis about which said arms are swingable whereby equal angular movement is imparted to the arms on sliding movement of the carriage on the carriage support, means constantly tending to turn said carriage support on its vertical axis whereby to maintain a tracer on one of said arms and a tool on the other thereof against the opposite sides of a pattern and a piece of work on said pattern and work supports respectively, a feed screw mounted for turning movement about its own longitudinal axis on said carriage support, said feed screw in threaded engagement with said carriage whereby on turning of the feed screw said carriage is slidinely moved in the direction of the length of said feed screw and relative to said carriage support, an electric motor on said carriage support and connected to drive said feed screw, an electric motor mounted on the arm the outer end of which mounts said tool, said arm mounting said tool for rotation relative to the arm, and a driving connection between said electric motor and said tool for rotating the latter from the former.
